UNITED STATES PATENT OFFICE.

CHARLES R. KLINE, OF BEECHWOOD, PENNSYLVANIA.

RADIATOR.

No. 884,739.

Specification of Letters Patent.

Patented April 14, 1903.

Application filed February 4, 1907. Serial No. 355,569.

To all whom it may concern:

Be it known that I, CHARLES R. KLINE, a citizen of the United States, residing in Beechwood, county of Cameron, State of Pennsylvania, have invented a new and useful Radiator, of which the following is a specification.

My invention relates to a new and useful improvement in a heating system and consists of means for throwing into and out of operation heating units, whereby the supply of heat is controlled.

It further consists of a series of radiator sections, forming a single radiator, which sections can be separately controlled.

It further consists of other novel features of construction, all as will be hereinafter fully set forth.

Figure 1 represents a partial elevation and 20 partial sectional view of a radiator embodying my invention, showing the same as broken in order to indicate that the radiator can be of any desired length. Fig. 2 represents a sectional view taken in a different 25 angle from that in Fig. 1. Fig. 3 represents slightly different form of construction. Fig. 4 is a vertical section similar to Fig 2, of the form shown in Fig. 3.

Similar numerals of reference indicate 30 corresponding parts in the figures.

Referring to the drawings:—In radiators now in use, I have found in practice, that it is impossible to regulate the heat and that in consequence when the radiator is turned on, 35 the weather being mild, the heat given off is too great, but when severe cold weather sets in, the radiating surface provided is not sufficient to properly heat the room in which the radiator is situated. In other words, it is 40 impossible with the heat radiating surface given to properly heat a room in very cold weather and yet in medium weather it is not possible to keep down the heat.

The purpose of my invention is to over- 45 come these defects and in carrying out the same I connect a plurality of heat units or heat radiating surfaces in such a manner that I can cut out or throw into operation the desired number, so that the amount of heat is 50 controlled, the heating medium being admitted into the upper or the lower section, as found most expedient.

In the drawings I have shown certain 55 forms for carrying out my invention, but I do not desire to be limited to the construction as

herein shown and described, as I may arrange the parts differently and employ other instrumentalities which will accomplish the same results.

1 and 2. designate sections of a radiator 60 which are formed of columns 3 and which sections are mounted one above the other and suitably connected together. Said sections may be of any number and any height or size, it being understood that each section is separate and independent excepting as herein-after described. In Fig. 1 I have shown each column as formed in one piece with the separating wall 4 therebetween, forming the upper and lower separate sections. In order to 70 supply the heating medium, I provide a supply pipe 5 leading from a suitable source of supply and from which lead branches 6 and 7.

8 in the present instance designates a two-way valve of well known form which controls the branches 6 and 7, it being noted that the branch 6 communicates with the interior of the section 1 while the branch 7 communicates with the interior of the section 2, the valve being so arranged that by properly 80 turning the same, the branch 6 only is opened so that a heating medium from the supply pipe 5 is directed into the section 1 without affecting section 2. If the heat is not sufficient from the section 1 by the proper manipulation of the valve 8, the branch 7 will also be opened to the supply pipe 5 so that the heating medium therefrom can pass through the branch 7 and to the section 2, thus providing additional heating surface, as will be 90 understood.

9 designates the main discharge pipe to which lead the branches 10 and 11, the former communicating with the interior of section 1 and the latter with the interior of the 95 section 2, a suitable two-way valve 12 of well known construction being provided for controlling said branches and said valve is adapted to be operated so that the discharge from the section 1 can pass into the exhaust 100 pipe 9 when section 2 is not in operation, but that when the said section 2 is also supplied to the heating medium, the valve 12 can be so turned that both the branches 10 and 11 are 105 in communication with the exhaust pipe 9, so that the discharge from each section can be cared for.

From the above, it will be understood that I am enabled to cut out heating sections, depending upon the amount of heat required or 110

if necessary, all sections can be thrown into operation. It will be further understood that any number of sections can be connected in such a manner that one or more may be thrown into or out of operation, it only being necessary to suitably control the same.

In Figs. 3 and 4 I have shown radiator sections 1 and 2 formed of the columns 3, which sections are mounted one above the other, 10 and are suitably connected, but in lieu of connecting the upper section with the branch from the supply I have formed a passage or communication 13 between the lower and upper sections in one of the columns 3, in the 15 present instance, in the first column and said passage 13 I control by means of a suitable valve 14, and operated by the hand-wheel 15 or other suitable means so that the sections can be cut off, one from the other or connected as desired, and I also provide another passage or communication 16 between the interior of the sections at the opposite end of the radiator sections for the discharge, said passage or communication 16 being controlled 20 by a valve 17 operated by a handle 18 or other suitable means, it being noticed that the separating walls 4 are employed between the sections as before. By this means it will be noted that the heating medium from the 25 supply pipe 5 is directed into the section 1, as heretofore and the medium cannot reach section 2 until the valve 14 is properly operated to permit passage thereof through the communication 13, at which time the sections 2 30 are also thrown into operation, it being understood that the valve 17 is likewise operated to permit the discharge reaching the discharge pipe 9, by passing into the section 1 and thence through the pipe 10 and valve

12, which has previously been properly operated therefor.

Having thus described my invention, what I claim as new and desire to secure by Letters Patent, is:—

1. A radiator formed of a plurality of vertically-disposed sections or columns each partitioned, forming upper and lower compartments, combined with means for independently governing the flow of heating agent to said upper and lower compartments 45 respectively.

2. A radiator formed of a plurality of vertically-disposed inter-communicating radiator sections or columns each partitioned, forming upper and lower compartments, 50 combined with means disposed in said partitions for controlling communication between the upper and lower compartments.

3. A radiator formed of a plurality of vertically-disposed inter-communicating radiator sections or columns each partitioned, forming upper and lower compartments, a supply pipe connected with the lower section, means disposed in said partitions for controlling the flow of the heating agent to the upper compartments, and a discharge pipe connected with the radiator.

4. A radiator formed of a plurality of vertically-disposed inter-communicating sections or columns, each partitioned, forming a plurality of compartments, combined with means for independently governing the flow of the heating agent to said plurality of compartments respectively.

CHARLES R. KLINE.
